CARD READER OR SIMILAR ARTICLE

Robert B. Chaffee, Boston, Mass., assignor to Honeywell Inc., Minneapolis, Minn.

Filed Sept. 1, 1970, Ser. No. 24,791

Term of patent 14 years

Int. Cl. D14—02

U.S. Cl. D26—5

Fig. 1

Fig. 2

Fig. 3

Fig. 4

Fig. 5

FIG. 1 is a front perspective view of a card reader embodying my new design;

FIG. 2 is a front elevational view thereof;

FIG. 3 is a top plan view of the card reader;

FIG. 4 is a left side elevational view thereof; and

FIG. 5 is a right side elevational view of the same.

The rear of the card reader, not shown, is substantially plain and unornamented.

I claim:

The ornamental design for a card reader or similar article, substantially as shown and described.
